(57) **CLAIM**

The ornamental design for a SAFETY VEST as shown and
described.

DESCRIPTION

FIG. 1 is a front perspective view from above of an embodiment
of the claimed design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1;

FIG. 6 is a top view of the claimed design of FIG. 1;

FIG. 7 is a bottom view of the claimed design of FIG. 1;

FIG. 8 is a front view of the claimed design of FIG. 1 when
the embodiment is turned inside-out;

FIG. 9 is a back view of the claimed design of FIG. 1 when
the embodiment is turned inside-out;

FIG. 10 is a front perspective view from above of an embodi-
ment of the claimed design;

FIG. 11 is a front view of the claimed design of FIG. 10;

FIG. 12 is a rear view of the claimed design of FIG. 10;

FIG. 13 is a left side view of the claimed design of FIG. 10;

FIG. 14 is a right side view of the claimed design of FIG. 10;

FIG. 12 is a top view of the claimed design of FIG. 10;

FIG. 16 is a bottom view of the claimed design of FIG. 10;

FIG. 17 is a front view of the claimed design of FIG. 10
when the embodiment is turned inside-out; and

FIG. 18 is a back view of the claimed design of FIG. 10
when the embodiment is turned inside-out.

The ornamental design which is claimed is shown in solid
lines in the drawings. The broken lines shown in FIGS. 1-9
depict portions of the safety vest that form no part of the
claimed design.

1 Claim, 18 Drawing Sheets
